(57) CLAIM

The ornamental design for a furniture component, as shown and described.

DESCRIPTION

FIG. 1 is a perspective view of a furniture component showing my new design.

FIG. 2 is another perspective view thereof.

FIG. 3 is a front elevational view thereof, with the rear, left and right-side elevational views being identical thereto.

FIG. 4 is a top plan view thereof; and,

FIG. 5 is a bottom plan view thereof.

The broken lines are for environmental purposes only and form no part of the claimed design.
